FLOOR SURFACER AND POLISHER

Filed April 16, 1931

Inventor
Martin H. Lang

By *Howard Kuehne*

Attorney

This application relates to an inexpensive floor surface and polishing device having a frame which is guided by an adjustable handle which may be set with the engaging end at different heights. The device is adapted

to move over the surface of the floor and to support the operating parts of the device. The device is particularly designed to surface or polish the floor in a manner which will be more easily operated and handled by different operators. A floor surface and polishing hood which is adapted to be carried on the surface of the floor and which is adapted to shield the floor surface and polishing member from the floor surface and polishing member.

FLOOR SURFACER AND POLISHER

Martin H. Lang, Minneapolis, Minn.

Application April 16, 1931, Serial No. 530,616

10 Claims. (Cl. 51—176)

My invention relates to floor surfacers and polishers of a simple character wherein a frame is formed to support the operating parts guided by an adjustable handle which may be set with the engaging end at different heights.

A feature resides in an inexpensive device used for surfacing or polishing floors and wherein the action is positive with all of the parts easily accessible. The frame of the device includes side members across which a platform extends and upon this platform the electric motor which is adapted to drive the surfacing member or wheel is carried. This places the motor in position so as to take advantage of the weight of the same in bearing against the polishing or floor surfacing roll in its operation. By this structure the machine or device may be made otherwise of a lightweight, making it easy to handle in moving it over the floor in operation.

20 A feature resides in a particularly formed frame, one side of which is capable of being sunk away from the end of the roller carrying the bearing in the outer free end of the same and thus permitting a new roll to be quickly and easily slipped into place on the supporting shaft which acts to steady the roll and carry it true in its rotation supported by the bearings in the forward end of the frame. Suitable clutch means are provided for engaging the roll to carry it about with the 30 supporting shaft.

The extension of the roll supporting shaft on one side of the frame permits the driving from the motor to be direct and close to the roll, while the motor is readily adjustable on the platform to regulate the tension in the driving belt or chain. The extension of the roll supporting shaft also permits the attachment of a floor surfacing member extending to one side of the frame of the machine so that the floor may be surfaced

40 close to the wall, like as has not been accomplished heretofore in so simple and practical a manner insofar as I know.

45 By means of a suitable shielding hood which is carried upon supporting pins on the front end of the frame of the machine, the surfacing or polishing roll is protected and shielded over the top and comparatively close to the floor engaging portion of the same. This hood may be quickly lifted off when it is desired. The roll providing the floor surfacing and polishing member may be of wood or any other suitable material and is adapted to readily receive steel wool, sandpaper, felt, or a brush member to operate in the manner desired.

The features and details will be fully defined in their structural relation one to the other.

In the drawing forming part of the specification:

Figure 1 is a perspective view of my floor sur- 60 facer and polisher.

Figure 2 is a plan view of a portion of the same with the handle portion removed and the movable side of the frame portion illustrated in dotted outer position.

Figure 3 is a bottom view similar to Figure 2.

Figure 4 is a section on the line 4—4 of Figure 2.

Figure 5 is a detail of a portion of the device.

The floor surfer A is constructed in an extremely simple form with caster wheels 10 carried by the rear end portions 11 of the frame B of the surfer and polisher A.

Extending from the rear end portions 11 I provide side members 12 and 13 which support the platform 14 between the same. This platform 14 is adapted to support the electric motor 15 which drives the floor surfer and polisher A in its operation.

The end portions which carry the caster wheels 10 are adapted to be connected to the adjustable 70 socket members 16 and these sockets 16 are adjustable by the quadrant 17 so that the sockets may be raised and lowered when it is desired. A suitable handle C with members 18 and a hand

engaging portion 19 are adapted to be connected 75 to the socket members 16. The adjustment of the socket members 16 through the quadrants 17 in relation to the ends 11 permits the hand engag- 80 ing portion 19 of the handle C to be raised or lowered to adjust the same to different heights.

85 This is a simple but effective structure which makes it easy to adjust the handle so that the polisher A may be more easily operated and handled by different operators.

The forward ends of the frame members 12 and 13 are adapted to support the bearings 20 and 21 which carry the operating shaft 22 between the same. The bearings 20 and 21 may be of any suitable nature, such as ball or roller

90 bearings, or any suitable bearing means to support the shaft 22 freely rotatable. The shaft 22 is adapted to be driven by the chain 23 from the motor 15. This chain 23 extends along the side 100 12 of the frame B of the machine A with a short projecting portion 22' extending on one side of the frame B, the purpose of which will be later described.

105 The side 13 of the frame B is pivotally mounted at 24 so that the frame portion 13 may swing out as illustrated in dotted outline in Figures 2 and 3.

This permits the bearing 21 to be swung away from the end of the shaft 22 and by loosening the nut 25 on the shaft 22 the roller 26 may be slipped off of the shaft 22. On the end of the 5 shaft engaged or carried in the bearing 20 I provide a clutch member 27 with projecting pins 28 which engage in complementary recesses formed in the roller 26. Thus by means of the nut 25 and the clutch 27, the roller 26 is held clamped 10 rigidly on the shaft 22 so as to rotate with the same.

The roll 26 may be of wood or other suitable material and by means of steel wool which is wrapped evenly around the roll 26, I provide a 15 floor surfacing wheel in the member 26 which will cut freely to resurface a floor very quickly. The motor 15 drives the shaft 22 at the desired speed so as to rotate the roll or wheel 26 and thus when this wheel is covered with steel wool which is wrapped in the desired direction so as to tighten 20 around the roll in its rotation and engagement against the floor, I provide a very desirable floor surfacing device in the machine A.

The roll 26 may be a felted roll with a polishing 25 felt over the surface of the same for polishing the floor, or this roll 26 may be in a brush formation for brushing and polishing a floor. Different rolls 26 may be adapted to the shaft 22 as just described, so that any roll of the desired 30 nature, such as 26, may be adapted readily to the machine A. To mount the roll 26 or disengage the same from the machine A, it is only necessary to free the swingable side member 13 by loosening the bolts 30 which hold the member 35 13 rigidly with the platform 14, and then swinging this member 13 out as illustrated in dotted outline. After this is accomplished, the nut 25 is disengaged and the roll 26 may be removed from the shaft 22. In the same manner a new roll 26 40 or of the character described may be applied to the shaft 22, the clutch 27 insuring the driving of any of the rolls 26 placed on the shaft. The shaft 22 extending through from one frame side to the other, such as 12 and 13, respectively, and being supported firmly in the bearings 20 and 21, provides a steady supporting means for any of the rolls 26 to insure even and true operation 45 thereof in the operation of the device A.

The extension 22' of the shaft 22 permits a 50 floor surfacing or polishing wheel such as 32 to be connected to the end of the shaft 22' and this wheel 32 projecting from the side of the machine and being formed with a connector attaching means such as the plate 33 which is held by the nut 34 into engagement with the collar 55 35 which supports the wheel 32 on the end 22', provides a surfacer and polishing wheel extending from the side of the machine so that the floor may be surfaced right close to the baseboard or 60 wall when it is desired.

To protect the roll 26 a simple hood D is formed 65 positioned to be supported by the pins 36 which project up from the top of the bearings 20 and 21. This hood D is set down onto pins 36 and may be easily lifted off when it is desired. The 70 hood D may be formed so as to extend in close proximity to the floor and closely around the roll 26 so as to protect the same and confine the material from the floor to below the machine A, keeping the dust and dirt away from the motor 15.

The open simple structure of my floor 75 surfacer and polisher A with the motor freely accessible, positioned in a manner to permit the weight of the same to assist in holding the polishing and surfacing roll 26 into firm engagement with the floor, together with the adjustable handle and

movable side portion 13 and the surfacing and polishing wheel 32 which is readily attachable, all co-operate together to provide a machine for surfacing and polishing floors of a very desirable nature. The motor A is held adjustable by the 80 bolts 37 which operate in the slots 38 in the bed 14. This permits the belt or chain 23 to be adjusted if it is desired.

A suitable electrical switch 40 positioned near the portion 19 permits the operator to turn the 85 motor 15 on or off at any time.

The floor surfacer and polisher A is of a simple 90 comparatively light weight nature having a compact structure with the parts arranged accessibly. The operating handle C is of a wide nature, making it very easy for the operator to handle the machine A, and the positioning of the motor on the platform close to the operating roll for surfacing or polishing the floor gives added advantages in the operation and handling of the machine.

This provides a machine of a character which 95 may be economically marketed, yet having important operating details which combine together to perform the functions in a very satisfactory manner.

In accordance with the patent statutes I have 100 described the principles of operation of the floor surfacer and polisher and while a particular structure is illustrated, together with the arrangement of the parts as defined, variations should be considered within the scope of the following claims.

I claim:

1. A floor surfacer and polisher including, an 110 adjustable handle member, a frame having side members, one of which is pivotally mounted to swing to one side, a platform carried on said side members, caster wheels supporting the rear end of said side members, shaft bearings carried at the 115 extreme front end of said frame, one of said bearings movable with the swinging of the swingable side member of said frame, a clutch plate rotatable with said shaft, a removable surfacing roll supported on said shaft removably engaged with said clutch plate, and an electric motor carried on said platform adjacent said roll adapted to operate the same.

2. A floor polishing device including, a frame 120 having a platform, side members for supporting said platform, one of said members being vertically pivotally mounted to swing to one side, 125 bearings carried at the extreme front ends of said members, caster wheels supporting the rear ends of said members, a handle adjustably mounted to raise and lower the operating position thereof at the rear of said frame members, a changeable floor surfacing roll, a shaft for removably supporting said roll in said bearings carried by the forward end of said frame members, a clutch 130 plate on said shaft engaging said roll when the same is in operative position, and an electric motor carried by said frame adjacent said roll whereby the weight of said motor acts to cause the floor surfacing roll to bear against the floor in 135 operation.

3. A floor surfacing device including, parallel 140 side members, a platform extending across between said side members, caster wheels supporting one end of said members, shaft bearings carried by the other end of said members, one of said members being pivotally mounted to swing with the bearing carried thereby to one side, bolts connecting said pivotally mounted side and said platform for holding said swingable side rigid to 145 150

- said platform, an interchangeable floor surfacing and polishing wheel carried by said bearings, and an electric motor mounted on said platform adapted to drive said surfacing wheel.
- 5 4. A floor surfacing and polishing device including, a frame formed with parallel side members, one of said members being pivotally mounted so that one end thereof may swing to one side, shaft bearings carried by said side members, a shaft carried in said bearings, a floor surfacing and polishing wheel carried on said shaft, the bearing in said swingable side being movable away from said shaft to permit the changing of said floor surfacing wheel, a removable hood over 80
10 said wheel, means for securing said hood to said side members to hold said pivotal side from pivoting, a platform adjacent said wheel between said sides, and an electric motor for driving said wheel adjustably mounted on said platform.
- 15 5. In combination, a pair of frame members, caster wheels for supporting one end of said frame members, a platform extending across between said frame members, one of said frame members being pivotally mounted to swing beneath said platform to one side thereof, bolts for holding said pivotally mounted side member rigidly to said platform, bearings carried by the ends of said side members opposite to said caster wheels, one of said bearings being movable with 90
20 the free end of said movable side member, a shaft for receiving different rolls mounted in said bearings, the rolls being placed on said shaft when said side member with the bearing is moved away from said shaft, and an electric motor mounted 95
25 on said platform for operating said shaft and the rolls mounted thereon.
6. A floor surfacing device including, a frame having a platform, side members under said platform adapted to support the same, one of which is 100
30 stationary while the other is pivoted to swing away to one side, a shaft bearing mounted in said stationary member, a shaft bearing mounted in the free end of said movable member, and means for 105
35 receiving a floor surfacing wheel on said shaft, means for locking said movable side member in operative position to support the end of said shaft, and slot means in said platform for permitting said locking means to swing free with said movable member when unlocked.
7. A floor surfacing device including, a frame comprising parallel side members, wheels supporting one end of each of said side members, means for pivotally mounting one of said side members, a floor surfacing roller mounted between the other ends of said side members, and removable connecting means extending over said roller to hold said sides in proper spaced relationship.
8. A floor surfacing device including, a frame comprising parallel side members, wheels supporting one end of said side members, means for pivotally mounting one of said side members to said frame, a floor surfacing roller mounted between the other ends of said side members, and a side member connecting hood for said floor surfacing roller to hold said sides in proper spaced relationship.
9. A floor surfacing device including, a frame, parallel side members on said frame, wheels supporting one end of said frame, means for pivotally mounting one of said side members to said frame, a floor surfacing roller mounted between said side members, bearings in said side members, pins in said side members, a hood over said roller, and means on said hood co-operable with said pins to hold said sides in proper spaced relationship.
10. A floor surfacing device including, a frame comprising parallel sides, wheels supporting one end of said side members, a platform connecting said sides, means for pivotally securing one of said side members to said platform, a floor surfacing roller mounted between the other ends of said side members, and side member connecting hood means detachably secured to said side members to hold the same in proper spaced relationship.
